UNITED STATES PATENT OFFICE.

ARTHUR DAVID NORTHRUP, OF ROCHESTER, NEW YORK.

COLLAPSIBLE LENSLESS FINDER FOR FOLDING CAMERAS.

1,345,224.

Specification of Letters Patent. Patented June 29, 1920.

Application filed June 20, 1919. Serial No. 305,453.

To all whom it may concern:

Be it known that I, ARTHUR D. NORTHRUP, a citizen of the United States, residing at Rochester, in the county of Monroe and 5 State of New York, have invented certain new and useful Improvements in Collapsible Lensless Finders for Folding Cameras; and I do hereby declare the following to 10 be a full, clear, and exact description of the invention, such as will enable others skilled in the art to which it appertains to make and use the same, reference being had to the accompanying drawings, and to the letters and figures of reference marked 15 thereon, which form a part of this specification.

This invention relates to new and useful improvements in collapsible instantaneous lensless finders for use on folding cameras 20 of various makes, and consists essentially in the provision of a collapsible finder made up of metallic parts pivoted together and which are adapted to slip over the side of the camera and when not in use may be 25 folded into a size to fit the vest pocket.

By the provision of a finder embodying the features of my invention, it will be noted that the same may be quickly applied to a camera, and pictures of objects 30 may be seen life size, and affording means whereby the object may be taken while moving rapidly, the device being utilized without lens.

My invention consists of a simple and efficient device of this character having various other details of construction, combination and arrangement of parts which will be hereinafter fully described, shown in the accompanying drawings and then specifically defined in the appended claims.

I illustrate my invention in the accompanying drawings which, with the numerals of reference marked thereon, form a part of this application, and in which:

45 Figure 1 is a perspective view of the finder opened for use,

Fig. 2 is an elevation of the finder folded, and

50 Fig. 3 is a detail perspective showing the manner of attachment of the device to a camera box.

Reference now being had to the details of the drawings by numerals:

55 1 designates a section of the frame having a circumferential flange 1', said flange having an opening 10, and at the lower por-

tion has lugs 1^x struck up therefrom, which are apertured to receive a pin 1^b upon which the clamping members 3 are pivotally mounted and which are provided with resilient fingers 3' adapted to clamp the box of a camera when the device is to be adjusted for use. Each of said members has a small lug 3^b struck up therefrom and which, when the member is swung, cause an open portion to contact with the end of the frame.

It will be noted that there are two of said resilient members, one upon either side, and which, when not in use, may be folded 70 against the solid portion of the frame, as shown in Fig. 2 of the drawings.

Pivotally mounted on one of the pins is a gage member 2^b which has a swinging movement on the pivot on which it is 75 mounted. Pivoted to the flange 1' is a link 5 which in turn is pivoted to a link 5', and which in turn is pivoted to a flange of the frame, which latter is provided with a central opening 8 directly opposite and centrally in alignment with the center of the opening 10. A stop 5^x is mounted upon the link 5 and is adapted to form a stop against which the arm 5' contacts when the links are drawn to the position shown in Fig. 1 85 of the drawings. Other links 4 are pivotally connected through the medium of the pins 4' with the side flanges of the frame 1, and are pivotally connected to the links 4^b which in turn are pivotally connected to 90 the angled ends of arms upon the frame 2. Each link 4 has a lug 4^c struck up from one edge thereof adapted to engage a notch 4^x formed in the link 4^b and tending to limit the throw of said links 4 and 4^b, causing 95 the same to be held with their opposite edges parallel and in the position shown in Fig. 1 of the drawings. The plate 2 is provided with a flange 2^x and its lower end is adapted to contact with the camera box. 100

In operation, when the device is opened up in the manner shown in Fig. 1 of the drawings, the fingers of the resilient members 3 clamp and hold the finder upon the camera frame, the object to be photographed 105 being seen life size with the naked eye, but looking through the circular outlined opening 8 in the plate 2 seeing the object outlined by the opening 10 in the frame 1.

In order to center the finder relative to 110 the door opening, the gage finger which is made of proper length, so that when the

point thereof is brought to the corner of the opening, as shown in Fig. 3 of the drawings, the finder will be exactly in the center of the side and direct line of lens of the camera. It will be understood that the finger point which is pivoted to the finder will be made to conform to different sizes of folding cameras.

By the provision of my improved collapsible instantaneous lensless finder, a simple device is afforded which may be applied to a camera and held against either eye which may look straight through the small circular aperture of the finder and within the field of the larger aperture of the finder may be focused quickly and with certainty of distinct outline and which will reduce to a minimum the waste of films heretofore experienced with finders commonly produced.

When the finder is not in use, it is removed from the camera and folded into a collapsed form, shown in Fig. 5 of the drawings, making a compact frame which may be easily carried in the vest pocket and always ready for use.

What I claim to be new is:

1. A collapsible instantaneous lensless finder for folding cameras, comprising a frame with an opening therein, and resilient means thereon for clamping the same upon the frame of a camera, an apertured plate having pivotal link connections with said frame and through the aperture of which plate an object to be photographed is adapted to be seen through the frame.

2. A collapsible instantaneous lensless finder for folding cameras, comprising a frame with an opening therein, and resilient means thereon for clamping the same upon the frame of a camera, an apertured plate having pivotal link connections with said frame and through the aperture of which plate an object to be photographed is adapted to be seen through the frame, and a gage pointer pivoted to the frame.

3. A collapsible instantaneous lensless

finder for folding cameras, comprising a frame with an opening therein, and lugs struck up from its edges, members pivoted to said lugs and having resilient fingers spaced apart adapted to frictionally clamp the frame of a camera, a gage finger pivoted to said frame, an apertured plate with an opening centrally in alignment with the opening in said frame, and links pivotally connecting said plate and frame.

4. A collapsible instantaneous lensless finder for folding cameras, comprising a frame with an opening therein, and provided with flanges, said frame having lugs struck up therefrom, resilient members pivotally mounted upon said lugs, and means for limiting the outer throw of said members, each member having clamping arms spaced apart, a pivoted gage pointer, a plate with an opening centrally in alignment with the opening in said frame, the ends of said plate having laterally extending arms with angled ends, pivotal link connections between said angled ends and the flanges of said frame, means for limiting the movements of said links.

5. A collapsible instantaneous lensless finder for folding cameras, comprising a frame with an opening therein, and provided with flanges, said frame having lugs struck up therefrom, resilient members pivotally mounted upon said lugs, and means for limiting the outer throw of said members, each member having clamping arms spaced apart, a pivoted gage pointer, a plate with an opening centrally in alignment with the opening in said frame, the ends of said plate having laterally extending arms with angled ends, pivotal link connections between said angled ends and the flanges of said frame, means for limiting the movements of said links, the bottom of said plate having an angled flange adapted to rest upon the frame of a camera.

In testimony whereof I hereunto affix my signature.

ARTHUR DAVID NORTHRUP.
